UNITED STATES PATENT OFFICE

154,032

DESIGN FOR A TRAILER FOR GRADING
ARTICLES

Earl A. Ernst, Bakersfield, Calif.

Application May 19, 1947, Serial No. 139,142

Term of patent 14 years

(Cl. D14—3)

To all whom it may concern:

Be it known that I, Earl A. Ernst, a citizen of the United States of America and a resident of the city of Bakersfield, in the county of Kern and State of California, have invented a new, original, and ornamental Design for Trailer for Grading Articles, of which the following is a specification, reference being had to the accompanying drawings, forming part thereof.

In the drawings:

Figure 1 is a top plan view of a trailer for grading articles, showing my new design,

Figure 2 is a side elevational view thereof,

Figure 3 is a side elevational view of the other side,

Figure 4 is a front elevational view only, and

Figure 5 is a rear elevational view only and

does not show any of the front portions of the trailer.

I claim:

The ornamental design for a trailer for grading articles, substantially as shown.

EARL A. ERNST.
